UNITED STATES PATENT OFFICE.

SAMUEL BUTT AND JOSEPH BUTT, OF NEW YORK, N. Y.

DESIGN FOR A PLATE AND THE LIKE.

54,238.

Specification for Design.

Patented Dec. 9, 1919.

Application filed December 7, 1918. Serial No. 265,798. Term of patent 3½ years.

To all whom it may concern:

Be it known that we, SAMUEL BUTT and JOSEPH BUTT, both citizens of the United States, and residents of the city of New York, borough of the Bronx, in the county of Bronx and State of New York, have invented a new, original, and ornamental Design for Plates and the like, of which the following is a specification, reference being had to the accompanying drawing, forming part thereof.

Fig. 2 is an edge view of the plate shown in Fig. 1.

We claim:

The ornamental design for a plate or the like as shown.

SAMUEL BUTT.
JOSEPH BUTT.
